[57] CLAIM

The ornamental design for a vehicle air deflector, as shown and described.

DESCRIPTION

FIG. 1 is a rear perspective view of a vehicle air deflector showing our new design;
FIG. 2 is a front perspective view thereof;
FIG. 3 is a left-side elevational view thereof, the right side being a mirror image of that shown;
FIG. 4 is a front elevational view thereof;
FIG. 5 is a rear elevational view thereof;
FIG. 6 is a top plan view thereof; and,
FIG. 7 is a bottom plan view thereof.
